DESIGN FOR A JEWELLED REFLECTOR

Louis A. Koch, Jr., Louisville, Ky.

Application February 27, 1937, Serial No. 67,882

Term of patent 7 years

To all whom it may concern:

Be it known that I, Louis A. Koch, Jr., a citizen of the United States, residing at Louisville, in the county of Jefferson and State of Kentucky, have invented a new, original, and ornamental Design for a Jeweled Reflector, of which the following is a specification, reference being had to the accompanying drawing, forming part thereof.

Fig. 1 is a plan view of the jeweled reflector showing my new design.

Fig. 2 is a side elevational view thereof, and Fig. 3 is a cross-sectional view on the line 3—3 of Fig. 2.

The dominant feature of my design resides in the portions shown in solid lines.

I claim:

The ornamental design for a jeweled reflector, as shown and described.

LOUIS A. KOCH, JR.
